ELECTROPAD

Fred J. Hart, Salinas, Calif., assignor to Electronic Medical Foundation, San Francisco, Calif., a corporation of California

Application October 21, 1949, Serial No. 122,783

12 Claims. (Cl. 128—24.1)

1

My invention relates broadly to a pad for body treatments and more particularly to a construction of alternating current-excited vibratory pad for applying beneficial effects to the body.

One of the objects of my invention is to provide a construction of electric pad for body treatment in which a multiplicity of individual groups of multiturn electrical windings electrically excited from alternating current are flexibly harnessed for imparting vibratory effects to the body, according to the frequency of the exciting current.

Another object of my invention is to provide a construction of alternating current-operated electric pad having groups of series connected multiple turn windings so laced that vibratory movement thereof according to the frequency of the applied alternating current is permitted while maintaining the groups of windings substantially coplanar.

Still another object of my invention is to provide a method of assembly of electric pad with respect to a multiplicity of protective cover members which render the use of the pad practical in treatment of the body.

Still another object of my invention is to provide a method of assembly of an electric pad with respect to a flexible fluid circulating enclosing cover, whereby a cooling fluid may be circulated around the pad while the pad is in use during body treatments.

A still further object of my invention is to provide novel features of construction of a flexible electric pad including grouped sections of an electric winding shaped to apply a massage action to body tissues in a most effective and efficient manner.

Other and further objects of my invention reside in a construction of electric pad as set forth more fully in the specifications hereinafter following, by reference to the accompanying drawings, in which:

Figure 1 is a perspective view of an electric pad constructed in accordance with my invention, and indicating the manner of electrically connecting the pad to an electrical power source; Fig. 2 is a perspective schematic view of the electric winding employed in the electric pad of my invention; Fig. 3 is a perspective view of a cover of fire resisting material, such as asbestos, within which I enclose the electric winding of Fig. 2, the view being partially broken away and shown in section for illustrating the heat insulation structure of the cover, and the view showing the asbestos cover before it is sewed across the end

thereof for enclosing the electric winding; Fig. 4 is a perspective view of a plastic bag which is used to enclose the asbestos cover of Fig. 3, the view being partially broken away to illustrate the insulation properties of the plastic bag, and being illustrated prior to a transverse sewing operation at the end of the plastic bag for enclosing the asbestos cover within the bag; Fig. 5 is a perspective view of a heat confining cover or wool blanket which I employ around the plastic bag of Fig. 4; Fig. 6 is a perspective view of the outer removable cover for the pad, which cover is formed from readily washable and launderable material for sanitary use over the pad of my invention; Fig. 7 is a curve diagram illustrating the characteristic of the pad of my invention over extended periods of time or use, and showing the slow heat rise incident to extended use of the pad; Fig. 8 is a curve diagram showing the electrical characteristics of the pad; Fig. 9 is a perspective view of a modified form of pad embodying my invention, in which cooling means are employed for substantially reducing the temperature at which the pad is applied to the body; Fig. 10 is a longitudinal sectional view taken through the form of pad illustrated in Fig. 9, and illustrating the association of the heating and cooling means within the pad, the view being taken substantially on line 10—10 of Fig. 13; Fig. 11 is a top plan view of the inside flexible rubber bag which encloses the winding in the form of my invention illustrated in Figs. 9—10, and showing particularly the relationship of the inside and outside bags; Fig. 12 is a transverse sectional view taken substantially on line 12—12 of Fig. 11, and showing the cooling fluid circulating space between the inner and outer flexible rubber bags in the form of my invention illustrated in Figs. 9—11; and Fig. 13 is a longitudinal sectional view taken substantially on line 13—13 of Fig. 11.

My invention is directed to a method of construction and structure of electric pad which I have found highly beneficial in treatment of the body. I employ an electric winding which is constructed in very special manner by arranging groups of sections of an electric winding excited from low frequency alternating current in an elongated or substantially elliptical flat coil, where the groups or sections of the winding are flexibly laced together by lacing means extending substantially radially with respect to the coil for forming a flat flexible coil unit. The coil unit consists of a total number of approximately 2500 turns of number 29 insulated copper wire.

The coil has an input of 205 milliamperes, and operates from a power supply source of 110 volts, 50-60 cycles. The electrical characteristic of the coil is such that a relatively constant, vibratory movement between groups of multturn laced windings in accordance with the frequency of the exciting alternating current is established with relatively slow temperature rise. The pad of my invention is readily distinguished from conventional electrical heating pads or blankets by the fact that the pad of my invention is intended for massage purposes rather than heat treatment purposes. Any heat rise in the device is purely incidental, and in one form of my invention is positively compensated and reduced by surrounding the unit with fluid circulating means by which the unit is cooled.

Referring to the drawings in more detail, reference character 1 designates the winding which is formed in groups of sections of wire which, in the example of my invention illustrated herein, consisted of a total number of approximately 2500 turns of number 29 copper wire, the groups or sections being indicated at 1a, 1b, 1c, 1d, 1e, 1f and 1g, which are disposed in coplanar relation in substantially elliptical contour. The groups or sections of wire are maintained in flexible relation by means of substantially radially extending lacing cords or textile members, which I have represented at 2a, 2b, 2c, 2d, 2e, 2f, 2g, 2h, 2i, 2j, 2k and 2l. These lacing cords are interwoven between the groups or sections of the winding and have their inside loops confined by an interconnecting cord 3 laced under tension criss-cross of the center of the inside group or section of said winding, and their outside loops interconnected by a confining cord 4. A flexible flat winding is thus provided which may be shaped to the contour of the body which is to be treated. The sections or groups of windings 1a, 1b, 1c, 1d, 1e, 1f and 1g are mutually displaceable within the limits of the interwoven connections 2a-2l, and vibrate at low frequency with respect to each other upon excitation of the windings from alternating current. The lacing cords arranged as explained herein are essential to the practical operation of the device of my invention as the vibratory movement of the groups or sections of the turns of wire is such that omission of the lacing results in misshaping of the electropad as the groups or sections of turns of wire work themselves into a twisted mass in the course of only a short period of use under the reaction forces resulting from the influence of the alternating and opposing magnetic fields. The lacing cords are flexible and are formed from insulation material. The cords exercise a sufficient degree of restraint on the groups or sections of turns of wire to prevent distortion or misshaping of the groups or sections of the turns of wire and maintain the said groups or sections of turns of wire substantially coplanar and yet allow shaping of the electropad to the contour of parts of the body where contact treatment with an irregular surface of a portion of the body is desired. Thus a massaging action is applied to the part of the body in contact with the outside cover of the pad immediately over the vibrating sections or groups of the winding.

The electrical circuit connection to the winding is established by means of the flexible electrical conductor 5, the end of which is fastened in fixed position to the outermost groups or sections of the winding 1a and 1b by means of fastening member 6 which is appropriately taped around

the groups or sections of the winding 1a and 1b. The outside of the coil is connected through conductor 5a with the outside turn of the group or section of the winding 1a. The several sections or groups of the coil are connected electrically in series one with the other, terminating at the inside turn of the group or section of the coil 1g. The innermost turn of the group or section of the coil 1g is connected to the thermal cutout switch represented schematically at 7, which connects in circuit with the conductor 5b leading to the input circuit conductors 5. The thermal cutout switch 7 limits the temperature rise in the winding, precluding any increase in temperature beyond a predetermined temperature for which the thermal cutout switch is designed and set.

In the form of my invention illustrated in Figs. 1-6, the groups of coils or sections constituting the winding are housed within the fire resisting or heat insulating flexible cover, which may be formed from asbestos and the like, as shown at 8 in Fig. 3. The asbestos cover in Fig. 3 has been shown with the end open prior to the lateral or transverse stitching operation at the end of the cover. After winding 1 is slipped longitudinally into the asbestos cover 8, the cover 8 is stitched along the end 8a thereof for closing the end of the asbestos cover around the winding 1, with a sufficient aperture for the passage of the conductor 5. The winding thus encased in the flexible asbestos cover 8 is then inserted into the flexible plastic bag represented at 9 in Fig. 4. The flexible plastic bag has been shown with an open end prior to stitching along a seam indicated at 9a therein for encasing the asbestos cover of winding 1 except for an outlet for the electrical conductors 5. The winding 1 thus encased in the flexible asbestos cover 8 and the flexible plastic bag 9 is ready for insertion into the heat confining cover or wool blanket 10 shown in Fig. 5. The heat confining cover or wool blanket 10 is provided with inside detachable snap fasteners represented at 10a for attachably maintaining the heat confining cover or wool blanket attachably and detachably in position over the asbestos and plastic bag covered winding 1. The winding 1, thus encased in the asbestos cover 8, the plastic bag 9 and the wool blanket 10, is then inserted into the outer cloth cover of cotton or other launderable material or linen, shown in Fig. 6, which is readily removable for sanitary purposes and interchangeable with a fresh cover. To render the outer cover 11 readily attachable and detachable, I provide a transverse row of snap fasteners represented at 11a on the end flap of the cover 11, coacting with complementary parts of the fasteners mounted on the cover 11. The electrical conductors 5 which extend outside of the several plies of covering material, include an electrical switch 12 in circuit therewith, and a suitable plug connector 14, for attachment to the source of power, such as 110 volts, 50-60 cycles alternating current.

In Fig. 7 I have shown a characteristic heating curve for the electrical winding, from which it will be seen that even after a period of three hours from the time of application of the exciting source, the temperature rise is appreciably below 70°. The magnetic flux which produces the vibratory action between the groups of turns of the winding during this time, however, remains substantially constant as represented in the curves shown in Fig. 8. The ordinates in the curves of Fig. 8 represent the magnetic field

strength in R. M. S. gausses, while the abscissa represent the distance from the center of the winding in inches. Curve A shows the distribution of the magnetic field longitudinally of the electromagnetic winding 1 on the major axis A—A' indicated in the graph to the right of the curves; while curve B shows the magnetic flux distribution along the transverse or minor axis of the winding 1, that is, axis B—B' of the winding. The relative constant or flat magnetic characteristic of the winding is well represented by curves A and B.

Inasmuch as the temperature of the winding must be maintained at a minimum while the magnetic field producing the vibratory effects is maintained at a maximum I have developed the form of my invention illustrated in Figs. 9-13 for positively reducing the temperature of the winding by compensating for tendency of any increase in temperature of the winding. In this form of my invention the winding 1 is encased in a fluid-tight bag or container 15, which I have designated as the inside flexible rubber bag. The flexible rubber bag 15 is formed in two parts vulcanized at their outer peripheries, represented at 15a in Figs. 11 and 12, with the electrical conductors 5 provided with rubber covered insulation and vulcanized at 15b at their entrance into the inside flexible rubber bag 15, forming a fluid-tight joint. The top and bottom flexible walls of the inside flexible rubber bag 15 are provided with a multiplicity of longitudinally extending outwardly projecting flexible rubber ribs 15c and 15d. The ribs 15c and 15d extend in spaced relation substantially parallel with each other and form longitudinal passageways or channels for fluid over the surface of the inside flexible rubber bag 15. An outside flexible rubber bag 16 is formed around the inside flexible rubber bag 15 by means of a pair of enclosing flexible rubber complementary bag portions shown at 16a and 16b. The complementary flexible rubber bag portions 16a and 16b are connected at the peripheries thereof, as shown at 17 by means of a vulcanized joint. The vulcanized joint 17 seals the entrance way 18 over the electrical conductors 5, and also seals the fluid intake connection 19 and the fluid outlet connection 20, at opposite ends of the outside flexible rubber bag, as shown in Figs. 9, 10, 11 and 13. 15 and 16 constitute jackets surrounding the winding 1 in spaced relation. The fluid intake connection tube 21 which is vulcanized into the outside rubber bag at 19, electrically connects with the flexible tube 22 leading to the fluid intake connection. The fluid discharge connection includes tube 23 sealed into the fluid outlet connection 20 and connected to the flexible tube 24 leading to the waste connection. The fluid entering the fluid intake connection 21 is distributed over the end surface of the inside rubber bag 15 and passes longitudinally between the ribs 15c and 15d to the discharge end of the rubber bag around both the top and bottom surfaces of the inside rubber bag 15, thereby cooling the winding 1 and compensating for any tendency toward increase of temperature therein.

The balance of the construction of the pad is as explained in connection with Figs. 1-6, that is, the outside rubber bag 16 is encased in the asbestos cover 8, which is in turn encased within the plastic bag 9, the plastic bag 9 being surrounded by the wool blanket 10 and the entire combination being encased within the sanitary cover 11. Suitable passageways are provided

through each of these plies for the fluid intake connection tube 21, the fluid discharge connection tube 23 and the electrical conductors 5.

The ribs 15c and 15d serve to space the inside rubber bag 15 from the outside rubber bag 16, so that clear passageways are maintained for the flow of the cooling fluid even under conditions where a person lies on the bags and considerably distorts the pad. The number of passageways extending longitudinally of the pad is sufficient to insure that at least some of the passages will be maintained clear for the circulation of the fluid even under distorted conditions of the pad.

I have found the pad of my invention highly beneficial in the treatment of the body. The massaging action to which the parts of the body contacted by the pad is subjected has proven stimulative and helpful to the healthful building up of tissue. The portability of the form of my invention illustrated in Figs. 1-6 renders this form of my invention highly useful and convenient for personal use by a patient without supervision. The form of my invention illustrated in Figs. 10-13 requires no more attention than is usually necessary in the conventional use of a hot water bag or douche.

I have found the pad of my invention particularly suitable as a pillow on which the patient may lie and receive the beneficial effects of the vibratory action. The differences in the pad of my invention as compared with the conventional electrical heating pad, can be more thoroughly appreciated when it is realized that the vibratory effects of the pad of my invention dominate any incidental electrical heating which accompanies the excitation of the winding. The groups or sections of the winding in the structure of my invention have mutually magnetic reactive effects, one with respect to another at the frequency of the applied alternating current. A vibratory action at low frequency is produced between the several groups or sections of the winding as the current is applied to the coil circuit, and these vibratory movements are effectively utilized in the application of the device of my invention for massaging the parts of the body against which the pad makes contact.

The particular method of lashing the electrical conductors 5 which carry the supply current to the winding 1 is very important, as in a device of this kind it is not unusual for a severe strain to be placed upon the electrical conductors 5 which develops a pull on the lead-in conductors 5a and 5b. For this reason the lead-in conductors 5a and 5b are looped upon themselves across several sections of the groups of windings and are fastened at positions which I have indicated at 5a' and 5a'' and at 5b' and 5b'' around certain of the groups of the sections of the winding in the manner shown. A strain placed upon the supply lead is thus more evenly distributed over the entire winding and does not tend to pull out the electrical supply lead or to fold or bend the winding. The fastenings 5a' and 5a'', and 5b' and 5b'' are so designed that these fastenings will give way before the winding distorts and accordingly the winding will not be injured or damaged. It will be observed that there is sufficient slack provided in the electrical conductors 5a and 5b by reason of the loops therein to take up undue strains caused by excessive pulls on the electrical conductors 5.

While I have described my invention in certain of its preferred embodiments, I realize that modifications may be made and I desire that it be

understood that no limitations upon my invention are intended other than may be imposed by the scope of the appended claims.

What I claim as new and desire to secure by Letters Patent of the United States, is as follows:

1. A flexible pad for application to the body comprising a multiplicity of sections of electromagnetic windings concentrically related one with respect to another with the turns thereof electrically connected in series, a multiplicity of flexible textile members interwoven around said sections of electromagnetic windings and disposed transversely of the direction of the turns of said windings for maintaining said sections of windings normally in coplanar relation and mutually displaceable within confined limits with respect to each other, a flexible rubber jacket enclosing said windings, a second flexible rubber jacket enclosing the aforementioned flexible rubber jacket but spaced therefrom for forming circulatory paths for cooling fluid between said jackets, means extending through said last mentioned jacket for introducing and discharging cooling fluid into the space between said jackets and means extending through both of said jackets for applying electrical energy to said windings from a source of alternating current for exciting said windings to produce a magnetic field and an incidental heat field where said magnetic field predominates said heat field while effecting movement of said sections of electromagnetic windings for producing a massaging action against the portion of the body to which said device is applied.

2. A flexible pad as set forth in claim 1 in which one of said jackets includes a multiplicity of substantially parallel extending spaced ribs maintaining said jackets in spaced relation while defining the fluid circulating channels between said jackets.

3. A flexible pad as set forth in claim 1 in which said first mentioned jacket includes flexible rubber ribs extending therefrom and establishing contacting relation with said second mentioned jacket for positively spacing said jackets while maintaining channels for the circulation of cooling fluid between said jackets.

4. A flexible pad for application to the body comprising a relatively flat multiple section electromagnetic winding, a fluid-tight flexible jacket surrounding said winding and deformable to accommodate the device to the shape of the body, a second fluid-tight flexible jacket surrounding the aforesaid fluid-tight flexible jacket and spaced therefrom to form a fluid circulating path between said flexible jackets, inlet and discharge connections sealed in, said second mentioned fluid-tight flexible jacket and terminating in the space between said fluid-tight jackets, a sealed connection for electrical conductors extending through both of said flexible jackets and establishing electrical connection with said multiple section electromagnetic winding from a source of alternating current, the sections of said multiple section electromagnetic winding being mutually displaceable for effecting a massaging action of the portion of the body to which the device is applied, and a heat insulation covering surrounding said last mentioned jacket.

5. A flexible pad as set forth in claim 4 which also includes a plastic cover surrounding said heat insulation covering, and a plurality of cloth covers surrounding said plastic cover, said cloth covers both being detachably removable and replaceable.

6. A device of the class described comprising a multiplicity of individual groups of multi-turn electrical windings electrically connected in series and energizable from a source of alternating current and normally disposed in coplanar relation, one group of windings centered within an adjacent group of windings, textile lacing cords interwoven with said individual groups of windings and disposed transversely of the direction of the turns thereof for normally maintaining said individual groups of windings in a relatively flat plane, one centered within the other, while allowing said individual groups of windings to vibrate relative to each other under the reaction of the alternating magnetic fields established therearound, for imparting a massaging action to an adjacent body substantially in surface contact therewith, said interwoven textile lacing cords terminating in loops externally and internally of the limits of said groups of windings, a confining cord interconnecting said outside loops and a separate tension cord interconnecting said inside loops for maintaining the shape and contour of said groups of windings under conditions of vibratory movement thereof.

7. A device of the class described as set forth in claim 6 in which the separate confining cord that interconnects the inside loops of said lacing cords extends criss-cross of the center of the inside group of said windings.

8. A device of the class described as set forth in claim 6, in which said individual groups of multi-turn electrical windings have a substantially elliptical contour and wherein said textile lacing cords extend substantially radially thereof and in which the separate confining cord that interconnects the inside loops of said lacing cords is stretched at angles with respect to the major axis of the elliptically contoured electrical windings which are greater than the angles between any one of said textile lacing cords and the said major axis of the elliptically contoured electrical windings for maintaining said windings in substantially coplanar relationship.

9. A flexible pad for application to the body comprising a multiplicity of sections of electrical windings disposed in substantially elliptical arrangement in coplanar relation and electrically connected in series, a plurality of flexible cords extending substantially radially with respect to said sections of windings and enveloping and mechanically interconnecting said sections, said flexible cords being interconnected adjacent their inner ends and also interconnected adjacent their outer ends by separate loop lacing members for maintaining said sections under normal condition in a relatively flat plane, while allowing relative displacement of said sections with respect to each other for effecting a massaging action with respect to the body and means connected to the windings adapted to be connected to an electrical circuit for energizing the pad.

10. A flexible pad comprising a multiplicity of individual groups of multi-turn electrical windings electrically connected in series and disposed in coplanar relation, textile cords interwoven with said individual groups of windings and disposed transversely of the direction of the turns thereof for flexibly maintaining said individual groups of windings in a relatively flat plane while allowing said individual groups of windings to vibrate relative to each other; a flexible jacket surrounding said windings and

forming a flow path for a multiplicity of channels of cooling fluid around said windings but out of contact therewith for compensating for tendencies of said windings to increase in temperature and means connected to the windings adapted to be connected to an electrical circuit for energizing the windings.

11. A flexible pad comprising a multiplicity of individual groups of multi-turn electrical windings electrically connected in series and disposed in coplanar relation, textile cords interwoven with said individual groups of windings and disposed transversely of the direction of the turns thereof for flexibly maintaining said individual groups of windings in a relatively flat plane while allowing said individual groups of windings to vibrate relative to each other; heat insulation means enclosing all of said groups of windings, a pair of conductors extending through one end of said heat insulation means, and secured to at least one of said groups of windings, said pair of conductors being fanned out into separate leads and said leads being individually looped upon themselves and secured at spaced positions to certain of said groups of windings in advance of the electrical connection thereof with said windings to provide sufficient slack therein whereby pull strains applied to said pair of electrical conductors are expended through the slack in said looped portions of said conductors attached to said groups of windings, said conductors being adapted to be connected to an electrical circuit for energizing said windings.

12. A flexible pad comprising a flat flexible electrical winding constituted by a multiplicity 35 304-5.

of sections of electrical windings connected in series, a multiplicity of flexible members enveloping said sections of said windings and disposed transversely of the direction of the turns thereof 5 and interconnecting said sections of electrical windings and allowing mutual movement between said sections while normally maintaining said sections in substantially coplanar arrangement for producing a massaging action to the part of the body against which the pad is applied 10 and a multiplicity of jackets enclosing said windings, the innermost jacket being formed from fire-resisting material, the adjacent jacket being formed from plastic material, the next adjacent jacket being formed from wool, and the last of said jackets being formed from cloth constituting a sanitary cover for said pad.
